UNITED STATES PATENT OFFICE.

MORGAN BRADFORD LEMLEY, OF FOOTE, IOWA.

BURIAL-CRANE.

SPECIFICATION forming part of Letters Patent No. 634,008, dated October 3, 1899.

Application filed May 31, 1898. Serial No. 682,210. (No model.)

To all whom it may concern:

Be it known that I, MORGAN BRADFORD LEMLEY, a citizen of the United States, residing at Foote, in the county of Iowa and State of Iowa, have invented certain new and useful Improvements in Burial-Cranes; and I do hereby declare the following to be a full, clear, and exact description of the invention, such as will enable others skilled in the art to 10 which it appertains to make and use the same.

My invention relates to certain new and useful improvements in burial-cranes, and has for its object to produce a device of this character which can readily be transported and 15 temporarily set up near a grave, where it can be operated to lift the casket from the hearse or the ground, swing it over the grave, and gently lower it to the bottom thereof, where its engaging parts may be released from above. 20 With these and other objects in view my invention consists in the novel details of construction and combination of parts to be clearly described in the following specification and fully set forth in the claims.

Referring to the accompanying drawings, forming a part of this specification, in which like characters of reference indicate similar parts throughout, Figure 1 is a side elevation of the crane, showing the casket in dotted lines. Fig. 2 is a perspective view of the hook-and-eye connection of the bands that surround the casket; and Fig. 3 is a transverse sectional view thereof, showing the method of operation of the means for disengaging the members.

In the drawings, 1 represents a pointed metallic cap threaded to the lower end of a vertical post or standard 3, having also secured thereon a bracket 28. In this bracket is 40 journaled a drum 4, carrying a ratchet-wheel 5, engaged by a pawl 6, pivoted on the bracket 28, and said drum is adapted to be operated by means of the crank-handle 7, secured on the shaft thereof.

A collar 8 supports the sleeve 9, which loosely surrounds the upper end of the standard 3 and is free to turn thereon, but is prevented from withdrawal by the pin 10 in the end of the standard. To the sleeve 9 is 45 secured a horizontal arm 11, supported by the brace 12, and said arm is preferably of a single piece of metal bent upon itself at 13,

with its two arms extending parallel to each other, as shown.

A bracket 14 is adjustably secured to the 55 arm 11 near its outer end and has journaled therein the pulleys 16, and the bracket 17, carrying the pulley 18, is also adjustably secured to the arm 11, but is located near its inner end.

Ropes 19 and 21 are wound on the reel 4 and pass over the pulleys 18 and 16 and are secured at their free ends to suitable bands 20 by means of rings 22. These bands are adapted to be passed around the casket and 65 have their ends engaged by means of hooks 23 and eyes 26 thereon, said hooks and eyes being formed of rectangular loops of wire, the hook being made narrower than the eye and having its end bent upward to form the nose 70 or bill, which has attached thereto a strap 25, passing under the eye, so that when the said strap 25 is drawn taut from above the eye will be elevated out of engagement with the hook.

From the foregoing it will be seen that the bands may be secured about a casket and the crank-handle turned so as to wind the hoisting-ropes on the drum, when the casket will be elevated and maintained in its suspended 80 position by means of the pawl engaging the ratchet-wheel, and thus preventing the retro-action of the drum. The casket may then be swung into a position directly above the grave by turning the arm 11 and gently lowered by 85 removing the pawl from engagement with the ratchet-wheel and allowing the crank to turn slowly. When the casket rests upon the ground, the bands are disengaged therefrom by drawing on the straps 25, and the ropes 90 are then wound on the drum, as before, and the operation is completed.

Having described my invention, what I claim as new, and desire to secure by Letters Patent, is—

1. A burial-crane consisting of an anchor adapted to be driven in the ground, a crane consisting of an upright adapted to be secured at its lower end to said anchor, a horizontal arm rotatably mounted on said upright, a 100 revolving drum journaled on said upright, a pair of pulley-wheels mounted on the horizontal arm, a rope passing over each pulley-wheel and thence around the drum, bands

secured to the lower ends of said ropes, said bands each having a suitable buckle and a suitable means for disengaging the members of the buckle after the casket is lowered.

2. A burial-crane consisting of an anchor adapted to be located in the ground, an upright attached at its lower end to said anchor, an arm rotatably secured to the upper end of said upright, a drum journaled on said upright, pulleys supported by said arm, said pulleys adapted to be moved longitudinally on said arm and secured in proper positions, ropes passing over said pulleys and thence around the drum, bands secured to the lower ends of said ropes, said bands adapted to surround the casket, each band having a suitable buckle and a means for disengaging the members of the buckle when the casket is lowered.

3. A burial-crane consisting of an anchor adapted to be made stationary with the ground, an upright fixed at its lower end to said anchor, an arm rotatably secured to the upper end of said upright, a drum journaled on said upright, pulley-wheels fixed on said arm, ropes passing over said pulley-wheels and thence around the drum, bands secured to the lower ends of said ropes, said bands adapted to surround the casket, hooks fixed to the end of each band, loops fixed to the

opposite end of each band, the hooks having at their hooked ends a horizontal section, a strap or other flexible connection secured to the horizontal ends of said hook, said strap adapted to pass under the upper end of the loop and when tightened adapted to disengage the loop from the hook.

4. A burial-crane consisting of an anchor adapted to be made stationary with the ground, an upright secured at its lower end to said anchor, an arm rotatably secured to the upper end of said upright, said arm consisting of a metallic tubing bent at an intermediate point and having its ends extending parallel to each other and being secured at its inner ends to the rotatable support, pulleys carried by said arm, ropes passing over said pulleys and thence around the drum, bands fixed to the lower ends of said ropes, said bands having at their ends suitable buckles and a means for disengaging the members of the buckles when the casket is lowered.

In testimony whereof I affix my signature in presence of two witnesses.

MORGAN BRADFORD LEMLEY,

Witnesses: W. W. BOLAND, J. L. LUTTON.
